CLAIM

The ornamental design for an all-terrain vehicle utility box,
as shown and described.

DESCRIPTION

FIG. 1 is a perspective view of the all-terrain vehicle utility box
of the present invention, the broken line showing a
portion of an all-terrain vehicle being for illustrative purposes
only and forming no part of the claimed design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.
